BOBBIN AND SPINDLE FOR SPINNING,
TWISTING, AND SIMILAR MACHINESJohn A. Kennedy, Saco, Maine, assignor to Saco-
Lowell Shops, Boston, Mass., a corporation of
Maine

Application October 15, 1938, Serial No. 235,295

4 Claims. (CL 242—46.2)

This invention relates to bobbins such as those used in spinning, twisting and other textile machines. It involves both the construction of the bobbins themselves and also their mounting on the spindles which support and drive them.

In recent years there has been a constant trend toward the use of larger packages and higher speeds in spinning, twisting, and similar operations. The increased package size is of advantage in permitting longer production runs between shut-downs for doffing, while a higher spindle speed means, other conditions being equal, a greater production per operating hour. This trend has progressed to a point where the package load and the rotative speed in many cases introduce difficulties which offset some of the advantages gained, and one of these is the greatly increased rate of wear of both the bobbins and spindles, particularly at the points where the two are in mutual contact.

It is the common practice so to mount bobbins upon their supporting spindles that the wall of the enlarged bore at the base of the bobbin is pressed down upon and maintains a driving fit in a circumferential line of contact with the tapered portion of the spindle, commonly termed the "acorn." The spindle blade projects upwardly from this acorn and is much smaller in diameter so that there is no contact between the bobbin and any part of the spindle above the acorn up to a point near the tip or nose of the bobbin where its bore is reduced in size sufficiently to engage the spindle blade and thus center the bobbin. However, the common practice is to maintain a clearance of a few thousandths of an inch between the blade and the bore of the bobbin at this point. Such a construction is considered necessary to permit the bobbin to be seated with a driving fit on the tapered acorn, since otherwise the blade, which often also is tapered near its upper end, might first engage the bobbin and so prevent the production of effective driving contact between the bobbin base and the acorn. In addition, some clearance between the bobbin tip and the blade is of advantage in producing better running conditions.

While such constructions have been successful heretofore, the use of higher speeds and larger and heavier yarn packages, coupled with the fact that such packages are never accurately balanced, has so increased the vibration and torque loading upon the spindle that the rate of wear of the parts has been greatly increased and has become an important practical factor. Frequently a slippage occurs between the bobbin and the

spindle, due to several causes, such as the increased drag of the traveller, or the vibration of the bobbin, with a resulting tendency of the bobbin to chatter or to creep upwardly along the taper of the acorn and thus reduce the frictional grip depended upon to drive it. When such slippage occurs, wear of the parts at the base of the bobbin progresses rapidly. Often, also, vibration of the bobbin whips the upper end of this member against the blade of the spindle, producing wear which increases very rapidly with an increase in the amplitude of relative oscillation of the parts. This also tends to loosen the driving engagement of the bobbin with the acorn.

The present invention is especially concerned with the foregoing considerations. It aims to improve the construction of both the bobbins, and in some cases of their supporting spindles also, with a view of minimizing those factors responsible for the high rate of wear and the unsatisfactory operating conditions, and to provide an arrangement in which the driving association of the spindle and bobbin will be made substantially more satisfactory and the useful life of these elements will be correspondingly increased.

The nature of the invention will be readily understood from the following description when read in connection with the accompanying drawing, and the novel features will be particularly pointed out in the appended claims.

In the drawing,

Figure 1 is a vertical, sectional view of a bobbin embodying features of this invention and mounted on a spindle in the usual manner;

Figs. 2 and 3 are similar views illustrating different embodiments of the invention; and

Fig. 4 is a vertical, sectional view of the top portion of a bobbin showing a further modification.

Referring first to Fig. 1, a spindle of a common type is there shown including a blade 2, whirl 3, and an acorn 4. Mounted on this spindle is a bobbin 5 comprising a hollow or tubular body similar in general form to the usual bobbins. It may be made of wood, in accordance with the usual custom, or of any other suitable material. The bore of the bobbin in the base portion thereof, instead of being made in the usual form, is tapered to conform to the taper of the acorn 4 upon which it fits. Such a complementary confirmation of these two elements produces a driving area of contact greater than that of the usual circumferential line contact which is produced in bobbins made by the usual methods.

This bobbin departs radically from prior con-

55

structions in the shape and arrangement of those parts which cooperate with the upper portion of the spindle blade. As shown, this part of the bobbin is equipped internally with a resilient bushing 6 made of rubber, cork, or equivalent materials, rubber being preferred. It is held in place by abutting its upper edge against a shoulder 7, which may either be formed on the lower end of a sleeve or plug cemented into the top of the bobbin, or by making the upper end of the bobbin of a corresponding shape so as to produce a shoulder integral therewith. The particular construction used will depend upon the method of assembly which it is desired to follow. The lower end of the bushing abuts against a tapered or frusto-conical metal washer 9 which is pushed into the bore of the bobbin and is held in place either by its frictional engagement with said bore or by resting on the upper shoulder of an annular portion 10 integral with the body of the bobbin.

The method of assembly at present preferred is to make the bobbin as illustrated in Fig. 1, to push the washer 9 into the bore from the top thereof, following this with the rubber bushing 6 and the sleeve 8, the latter being cemented in place.

Such a bobbin can readily be slipped on and off the spindle, whether the latter is stationary or running. Preferably the bore of the bushing 30 is made very slightly larger, say one or two-thousandths of an inch, than the outside diameter of the spindle, and, because of its resilient nature, it will have a high degree of durability against any peening or frictional action of the spindle blade at its area of contact therewith. In addition, it preferably exerts a slight yielding grip on the blade so that it supplements the rotating drive chiefly produced by the fit of the tapered base on the acorn 4 because of the high 35 co-efficient of friction common to resilient materials of this nature when acting upon metallic surfaces. It also improves the running conditions of the bobbin, both because of its ability to absorb vibrations within its own mass, and 40 also for the reason that it affords the bobbin more latitude in finding its own center of rotation. A firmer driving contact also is produced by the better fit of the bobbin base on the slow taper of the acorn 4, as above mentioned.

It will be observed that the tapered washer 9 50 serves not only as a positioning element for the bushing 6 but also aids in guiding the tip of the blade into the bore of the bushing when placing the bobbin on the spindle.

By slight modification, as shown in Fig. 2, the construction above described lends itself to an arrangement in which the bobbin may be supported and driven from its upper end. This embodiment of the invention is like that shown 55 in Fig. 1 except for the fact that the bore of the resilient bushing 6' is tapered to fit the tapered upper end portion of the spindle blade 2', and the acorn 4 of Fig. 1 is replaced with a stepped construction having an annular shoulder 12 adapted to act as a stop for the lower end of the bobbin. That portion of the acorn above the shoulder is so reduced in diameter that a radial clearance of in the neighborhood of ten to twenty-thousandths of an inch is provided between it 60 and the bore of the bobbin, and the latter is made approximately cylindrical in form throughout the entire distance below the part 10. If desired, the shoulder 12 may be entirely omitted. In any event, the bobbin should not be seated upon it with sufficient pressure to prevent the bobbin

from moving radially relatively to the spindle to any degree necessary to enable it to find its own center of rotation.

This arrangement for suspending the bobbin from the rubber bushing 6' and driving the bobbin through the bushing is very useful in many situations and has the advantage of minimizing wear of the mutually contacting surfaces of the spindle and bobbin and giving the bobbin a better opportunity to centralize itself on the spindle. 10

Fig. 3 shows a construction in which a spindle like that illustrated in Fig. 1 is used, but the mounting of the bobbin on the spindle is effected through the use of resilient means at both the top and bottom of the bobbin. In this construction the bobbin 14 is similar to that shown in Fig. 1 but is provided at its upper end with an inwardly projecting annular boss 15 having a shoulder at its lower end against which the upper end of the rubber bushing 16 bears. The bushing is followed into place by a conical metal washer 17, similar to that shown in Figs. 1 and 2 at 9, and operating through its frictional engagement with the bore of the bobbin as the sole means for holding the bushing up against the part 15. In addition, it performs the function of piloting the tip of the spindle blade into the bore of the bushing in placing the bobbin on the spindle. This same mounting of the bushing can be used in either of the forms of the invention illustrated in Figs. 1 and 2. 20

Another resilient bushing 18 is mounted in the base portion of the bobbin and is held in place by an annular metal shield or ferrule 20. This member initially is made of channel section and it embraces the lower portions of both the bobbin and the bushing, its upper edges being crimped into both members. Thus it completely covers and protects the lower edges of the parts 14 and 18, it assists in guiding the tip of the blade 30 into the bore of the bobbin, and it prevents the rolling up of the lower edge of the bushing 18 which otherwise would be likely to occur. These parts can readily be made of such dimensions that the ferrule 20 does not interfere with the engagement of the bushing 18 with the acorn 4, ample clearance being provided between the latter and the shield when the bushing is in full contact with the acorn. 40

A further arrangement for mounting the resilient bushing in the upper end of the bobbin is illustrated in Fig. 4. Here the bobbin 21 is provided with an annular internal boss 22, integral therewith, and the bushing 23 is seated upon the shoulder at the upper end of this boss. It is held in place by a metal washer 24 forced into the upper end of the bore of the bobbin where it may substantially close said bore. 55

In all of these constructions the rate of wear of the mutually contacting surfaces of the bobbin and spindle are greatly reduced, vibration of the bobbin on the spindle is cushioned and minimized, and the bobbin is afforded the degree of movement relatively to the spindle necessary to establishing and maintaining smooth running 60 conditions. Thus the invention makes it entirely practical to gain the advantages of the higher spindle speeds and the larger packages without incurring the objections to both which have been experienced in using prior constructions. 65

While I have herein shown and described typical embodiments of my invention, it will be understood that the invention may be embodied in other forms without departing from the spirit or scope thereof. Also, that the use of such a con- 70

struction as that shown in Fig. 3 for improving the association between the base portion of the bobbin with the acorn of the spindle may, if desired, be used independently of any such cushioning means at the tip of the bobbin as those above described.

Having thus described my invention, what I desire to claim as new is:

1. A bobbin for use in spinning, twisting and similar machines, said bobbin comprising a tubular body adapted to be slipped on and off a spindle in such a machine, a resilient bushing in the upper part of said body adapted to yieldingly center the upper portion of the bobbin on the spindle blade, means for holding said bushing in a fixed position in said body including a shoulder in the bobbin against which one end of the bushing bears, and a tapered frusto-conical sheet metal washer engaging the opposite end of said bushing and serving to guide the tip of the spindle blade into the bore of the bushing when said bobbin is slipped on the spindle.
2. A bobbin of the character described, comprising a tubular body adapted to be slipped on and off a spindle and having a resilient tubular bushing in the lower portion thereof adapted to yieldingly engage a cooperating portion of the spindle to center the base of the bobbin on the spindle, and an annular ferrule crimped around the lower edges of the bobbin and bushing and having a portion extending upwardly inside said bushing and serving to hold the latter in place, the internal diameter of the portion of said bushing adapted to engage the spindle being less than that of the ferrule.

3. A bobbin for use in spinning, twisting and similar machines, said bobbin comprising a tubular body adapted to be slipped on and off a spindle in such a machine, a resilient bushing in the upper part of said body adapted to closely encircle the spindle blade and to yieldingly center the upper portion of the bobbin on the spindle blade, a sheet metal washer of frusto-conical form, the lower and larger end of which engages the bore of the bobbin, the smaller end being directly upwardly, the lower end of said bushing bearing on said washer, and means in said bobbin above said bushing and against which the upper end of the latter bears and which cooperates with said washer in holding the bushing in its operative position.

4. A bobbin of the character described, comprising a tubular wooden body adapted to be slipped on and off a spindle and having rubber bushings in the upper and lower portions thereof adapted to yieldingly engage cooperating portions of the spindle to center the bobbin on the spindle, a ferrule securing said lower bushing in place in said bobbin body and protecting the lower edges of both said body and said bushing while leaving the spindle engaging portion of the bushing projecting inwardly beyond said ferrule, a frusto-conical sheet metal washer engaging the bore of said bobbin and supporting the lower end of said upper rubber bushing, and means engaging the upper end of the latter bushing to cooperate with said washer in holding it in place in said bobbin.

JOHN A. KENNEDY. 35

CERTIFICATE OF CORRECTION.

Patent No. 2,236,178.

March 25, 1941.

JOHN A. KENNEDY.

It is hereby certified that error appears in the printed specification of the above numbered patent requiring correction as follows: Page 1, second column, line 19, for the word "of" after "view" read --to--; page 3, first column, line 18, claim 1, strike out "tapered"; and that the said Letters Patent should be read with this correction therein that the same may conform to the record of the case in the Patent Office.

Signed and sealed this 6th day of May, A. D. 1941.

(Seal)

Henry Van Arsdale,
Acting Commissioner of Patents.
